LID SUPPORT

Emory Glenn Simpson, Detroit, Mich., assignor
to Ternstedt Manufacturing Company, Detroit,
Mich., a corporation of Michigan

Application February 15, 1937, Serial No. 125,722

10 Claims. (Cl. 217—60)

This invention relates to a lid support.

A deck lid support is old and well-known such as are used for supporting the hinged deck lid for the rear compartment of an automobile wherein the operation of the lid support is such that upon fully raising the lid and then slightly lowering the same the lid support is automatically latched and thus supports the lid in raised position and wherein the lowering of the lid is preceded by a slight raising of the same which automatically unlatches the lid support to permit collapsing of the same. Although this general type of lid support is old, the lid supports heretofore used have not been altogether satisfactory because the automatic latching and unlatching arrangement was often defective and the lid support lacked the necessary strength to support the lid. When a pair of this type of lid supports is used with a lid, the need for dependable operation of automatic latching and unlatching arrangement under all circumstances is obvious. In particular the one trouble which has arisen is that the one lid support will automatically unlatch and the other one remain latched when the operator attempts to lower the lid.

It is an object of this invention to produce a lid support of the general type above-described which is dependable in operation, rugged and yet simple in structure.

30 In the drawings:

Fig. 1 is a fragmentary side elevation of an automobile showing the deck lid in raised position.

Fig. 2 corresponds to Fig. 1 but showing the deck lid closed.

Figs. 3, 4, 5 and 6 illustrate the latching and unlatching of the lid support during the raising and lowering of the lid.

Fig. 7 is a section along the line 7—7 of Fig. 4.

40 Fig. 8 is a detail sectional view showing the counterbalancing spring.

Fig. 9 is a side elevation of a modified form of the lid support.

Fig. 10 is a section along the line 10—10 of Fig. 9.

Referring more particularly to the drawings there is shown an automobile having the rear deck lid 1 hinged to the body as at 2. The lid is arranged to be supported in raised position by a lid support comprising two tubes 3 and 4. The tube 3 is slidably telescoped within the tube 4. The tube 3 is hinged to the deck as at 5 and tube 4 is hinged to the deck lid 1 as at 6. The upper end 7 of the tube 3 is closed. The tube 3 has fixed thereto a pin 8 positioned diametrically of

the tube 3. The pin 8 has an end 9 which extends beyond the circumference or outer face of the tube 3. The tube 4 is provided with a longitudinal slot 10 in which the outer end 9 of the pin 8 slides to permit the sliding of the tube 3 within the tube 4 during the raising and lowering of the lid 1. A clamp 11 is secured on the outer end of the slotted tube 4 to prevent the same from spreading.

For the purpose of latching the lid support in raised position a keeper for, and arranged to co-operate with, the pin 8 is pivotally supported on the tube 4. To this end a bracket 12 is welded or otherwise fixed to the outside of the tube 4. The keeper 13 is hinged to the bracket 12 by the pin 14 to provide a friction joint sufficient to retain the keeper in whatever position it is swung.

The keeper 13 comprises a metal stamping provided with a flange 15 which cooperates with an island 16 welded or otherwise fixed centrally of the keeper 13 to form a trackway along which the pin head 9 travels during the latching and unlatching of the support. The flange 15, as shown in the drawings, extends completely around the keeper except for the pivoted or upper end of the same. At this point the two ends of the flange 15 are positioned on opposite sides of the slot 10 and cooperate to form a mouth 17 through which the pin head 9 enters and leaves the keeper 13. The flange 15 is also formed with cam faces 20 as shown in the drawings and described below. The keeper trackway comprises a raising trackway portion 18 on the one side of the keeper and a lowering trackway portion 19 on the other side of the keeper. A switch is provided over the end 30 of the lowering trackway 19 in the form of a flat spring 20 which is spot welded or otherwise fixed adjacent its end as at 21 to the island 16.

A coil spring 22 is fixed within the tube 4 between the bottom 23 of the same and the closed end 7 of the other tube 3. For retaining the spring 22 in position within the tube 4 one end 24 of the spring is fixed in an opening 25 in the tube 4. The spring 22 serves as a shock absorber when the lid 1 is lowered and also serves as a counterbalancing spring to assist in the raising of the lid 1 during a portion of its upward swing. As the lid approaches lowered position the closed end 7 of the tube 4 engages and compresses the spring 22 whereby the spring serves both as a shock absorber and counterbalance for the lid.

The operation of the lid support is as follows: The position of the parts when the lid is lowered is shown in Fig. 2. As the lid is raised the pin 9 travels along the slot 10 where it passes through

the mouth 17 of the keeper and then travels along the raising trackway 18 (the switch spring 20 keeping the pin from entering the lowering trackway 19) and upon engaging cam surface 58 5 swings the keeper counter-clockwise until it strikes the corner 27 (Fig. 3) which serves as a stop to arrest upward movement of the lid 1. The lid is now in fully raised position. Upon lowering the lid the pin 8 strikes the cam face 28 10 which causes the keeper 13 to swing counter-clockwise from the position shown in Fig. 3 to that shown in Fig. 4 and the pin 8 engages the notch 29 in the island. The lid is now in raised latched or supported position. To lower the lid 15 15 the same is first raised slightly whereupon the pin 8 passes out of the notch 29, strikes the cam surface 30 to swing the keeper 13 still further counter-clockwise from the position shown in Fig. 4 to that shown in Fig. 5 until the pin 8 reaches corner 31 of the keeper 13 which serves as a stop to arrest further upward swinging of the lid 1. At this time the lid can now be lowered and the pin head 9 travels along the lowering trackway 19, as shown in Fig. 6, and then past the switch 25 20 through the mouth 17 of the keeper 13 back to the position shown in Fig. 2.

The modified form of the lid support, shown in Figs. 9 and 10, differs primarily from the principal form only in that the telescoping members 30 33 and 34, which correspond to tubular members 3 and 4, are of channel section rather than tubular, and in that a convolute counterbalancing spring 35 is provided rather than the helical counterbalancing spring 22 of the principal form. The 35 convolute spring 35 has one end 36 secured in the end of the support pin 37 fixed to the channel member 33. The support pin 37 is journaled in fixed bracket 40 and thus serves as a pivot about which member 33 swings. The other end 38 of the 40 spring 35 engages a lug 39 on the fixed bracket 40 as shown. Thus the counterbalancing spring 35 counterbalances the weight of the lid throughout the entire raising and lowering of the same.

I claim:

45 1. A lid support comprising a pair of telescoped members arranged to slide one within the other during the raising and lowering of the lid, a keeper swingably mounted on one of said members, said member also having an elongated slot, 50 a pin fixed to the other member and arranged to travel in said slot during the sliding of the one member within the other, said swingable keeper having a trackway along which said pin travels and a stop for said pin, said trackway being arranged whereby the pin swings said keeper as it travels along said trackway to engage said pin and stop and thereby latch said support in lid supporting position.

55 2. A lid support comprising a pair of telescoped members arranged to slide one within the other during the raising and lowering of the lid, a keeper swingably mounted on one of said members, said member also having an elongated rectilinear slot extending lengthwise thereof, a pin fixed to the other member having a portion projecting into said slot and arranged to travel therein during the sliding of the one member within the other, said swingable keeper having a trackway along which said pin travels and a stop for said pin, said trackway being arranged whereby the pin swings said keeper as it travels along said trackway to engage said pin and stop and thereby latch said support in lid supporting position.

60 3. A lid support comprising a pair of hollow telescoped members arranged to slide one within

the other during the raising and lowering of the lid, a keeper swingably mounted on the outside of the outer telescopic member, said outer member having an elongated slot, a pin fixed to the inner member having a portion projecting into said slot and arranged to travel therein during the sliding of the one member within the other, said swingable keeper having a trackway along which said pin travels and a stop for said pin, said trackway being arranged whereby the pin swings said keeper as it travels along said trackway to engage said pin and stop and thereby latch said support in lid supporting position.

65 4. A lid support comprising a pair of telescoped members arranged to slide one within the other during the raising and lowering of the lid, a keeper swingably mounted on one of said members, said member also having an elongated slot, a pin fixed to the other member and arranged to travel in said slot during the sliding of the one member within the other, said swingable keeper having an island and a trackway around said island including raising and lowering trackway portions along which said pin travels and a plurality of stops for said pin, said pin, trackway, 70 island and stops being arranged whereby the pin swings said keeper upon raising of the lid to engage the pin and one of said stops to arrest further raising of the lid and upon lowering the lid to engage said pin in the second of said stops to hold the lid in raised position and upon further raising of the lid disengages said pin and second stop and engages said pin with a third stop to again arrest further upward movement of the lid prior to lowering the same.

75 5. A lid support comprising a pair of telescoped members arranged to slide one within the other during the raising and lowering of the lid, one of said members having an elongated rectilinear slot extending lengthwise thereof, a keeper swingably mounted on said last mentioned member and arranged to swing transversely of the said slot, a pin fixed to the other telescoped member and projecting into said slot and arranged to travel therein during the sliding of the one member within the other, said swingable keeper having a trackway along which said pin travels and a stop for said pin, said trackway also including a mouth normally aligned with the elongated slot whereby the pin enters said keeper and trackway through said mouth and swings the keeper as it travels along said trackway to engage said pin and stop and thereby latch said support in lid supporting position.

80 6. A lid support comprising a pair of tubular telescoped members arranged to slide one with the other during the raising and lowering of the lid, a keeper, a friction hinge for swingably mounting the keeper on one of the tubular members, said member also having an elongated rectilinear slot extending lengthwise thereof, a pin fixed to the other member having a portion projecting into said slot and arranged to travel therein during the sliding of the one tubular member within the other, said pin also serving as a sliding key to prevent rotating of the one tube about the other, said swingable keeper having a trackway along which said pin travels and a stop for said pin, said trackway being arranged whereby the pin swings said keeper transversely of the said slot as it travels along said trackway to engage said pin and slot and thereby latch the said support in lid supporting position.

85 7. A lid support comprising a pair of channel

35

- telescoped members arranged to slide one within the other during the raising and lowering of the lid, a keeper, a friction hinge for swingably mounting the keeper on one of the channel members, said member also having an elongated rectilinear slot extending lengthwise thereof, a pin fixed to the other member having a portion projecting into said slot and arranged to travel therein during the sliding of the one channel member within the other, said pin also serving as a sliding key to prevent rotating of the one tube about the other, said swingable keeper having a trackway along which said pin travels and a stop for said pin, said trackway being arranged whereby the pin swings said keeper transversely of the said slot as it travels along said trackway to engage said pin and slot and thereby latch the said support in lid supporting position.
8. A lid support comprising a pair of hollow telescoped members slideable one within the other during the raising and lowering of the lid, a keeper, a friction hinge for swingably mounting the said keeper on one of said telescoped members, said member also having an elongated slot across which the keeper is arranged to swing, a pin fixed to the other telescopic member and arranged to travel in said slot during the sliding of the one member within the other, said swingable keeper having an island and a peripheral flange cooperating with the said island to form a trackway including raising and lowering trackway portions along which said pin travels, the said flange terminating on opposite sides of the said slot to form a mouth through which the pin enters said trackway, said island having a stop located on the side of the island remote from the said mouth, a pair of stops positioned on opposite sides of the said stop in the island, said island and flange having cam surfaces cooperating with the said stops whereby when the lid is raised the pin swings the keeper and engages one of said stops on one side of the island to arrest upward movement of the lid and upon lowering of the lid said pin is directed into engagement with the stop in the said island to hold the lid in raised position and upon further raising of the lid the pin disengages said island stop and is directed into engagement with the stop on the opposite side of the island to again arrest further upward movement of the lid prior to lowering the same.
9. A lid support comprising a pair of hollow telescoped members slideable one within the other during the raising and lowering of the lid, a keeper, a friction hinge for swingably mounting the said keeper on one of said telescoped members, said member also having an elongated slot across which the keeper is arranged to swing, a pin fixed to the other telescopic member and arranged to travel in said slot during the sliding of the one member within the other, said swing-
- able keeper having an island and a trackway about said island including raising and lowering trackway portions along which said pin travels, the said trackway having a mouth opening into the said slot through which the pin enters said trackway, said island having a stop located on the side of the island remote from the said mouth, a pair of stops positioned on opposite sides of the said stop in the island, said island and trackway having cam surfaces cooperating with the said stops whereby when the lid is raised the pin swings the keeper and engages one of said stops on one side of the island to arrest upward movement of the lid and upon lowering of the lid said pin is directed into engagement with the stop in the said island to hold the lid in raised position and upon further raising of the lid the pin disengages said island stop and is directed into engagement with the stop on the opposite side of the island to again arrest further upward movement of the lid prior to lowering the same.
10. A lid support comprising a pair of hollow telescoped members slideable one within the other during the raising and lowering of the lid, a keeper, a friction hinge for swingably mounting the said keeper on one of said telescoped members, said member also having an elongated slot across which the keeper is arranged to swing, a pin fixed to the other telescopic member and arranged to travel in said slot during the sliding of the one member within the other, said swingable keeper having an island and a peripheral flange cooperating with the said island to form a trackway including raising and lowering trackway portions along which said pin travels, the said flange terminating on opposite sides of the said slot to form a mouth through which the pin enters said trackway, a yieldable switch positioned at the end of the lowering trackway portion for shunting the pin into the raising trackway portion upon raising the lid and permitting the pin to pass out of the lowering trackway upon lowering of the lid, said island having a stop located on the side of the island remote from the said mouth, a pair of stops positioned on opposite sides of the said stop in the island, said island and flange having cam surfaces cooperating with the said stops whereby when the lid is raised the pin swings the keeper and engages one of said stops on one side of the island to arrest upward movement of the lid and upon lowering of the lid said pin is directed into engagement with the stop in the said island to hold the lid in raised position and upon further raising of the lid the pin disengages said island stop and is directed into engagement with the stop on the opposite side of the island to again arrest further upward movement of the lid prior to lowering the same.

EMORY GLENN SIMPSON. 60
